United States Patent Office.

OLIVER GUINAND, OF VICKSBURG, MISSISSIPPI.

Letters Patent No. 66,325, dated July 2, 1867.

INSTRUMENT FOR PERFORATING CIGARS.

The Schedule referred to in these Letters Patent and making part of the same.

TO ALL WHOM IT MAY CONCERN:

Be it known that I, OLIVER GUINAND, of Vicksburg, in the county of Warren, and State of Mississippi, have invented a new and improved Cigar-Point Perforating Machine; and I do hereby declare that the following is a full, clear, and exact description thereof, which will enable others skilled in the art to make and use the same, reference being had to the accompanying drawings, forming part of this specification.

This invention relates to a machine for perforating the points of cigars, and consists of a block of wood or other suitable material seated on a spring in another hollow block having spikes hinged in its walls, and passing through slots or mortises in the shape of right-angled triangles in the walls of the inner block. In the accompanying drawings—

Figure 1 is a vertical section of my cigar-point perforating machine, and

Figure 2 is a horizontal section thereof at line *z z*.

Similar letters of reference indicate like parts.

A is a hollow block of wood or other suitable material; a second hollow block, B, being set in the block A upon the spring *a*, which rests on the movable bottom *y*. *b* is a wadding placed between the spring *a* and block B. C C are spikes pivoted at *c*, in the slots or mortises *F* in the walls of the block A, and passing through the right-angled triangular mortises *D* in the block B, and beneath the metal lining *E* of the hollow block B. The cigar being placed in the hollow of the block B, the block is forced down upon the spring and the four spikes run through the slots into a horizontal position, piercing the point of the cigar. The pressure being withdrawn, the block returns, carrying the spikes back to an angle of about forty-five degrees. In fig. 1 the spring is seen relaxed and the spikes inclined at such angle. In fig. 2 the spring is compressed and the spikes in a horizontal position penetrating to the middle of the block B. The bottom *y* may be provided with holes to enable it to be screwed to the counter or other suitable place.

What I claim as new, and desire to secure by Letters Patent, is—

1. The hollow block A, having the spikes C pivoted in slots or mortises in its walls, as and for the purposes described.

2. The hollow block B, having right-angled triangular slots or mortises D to receive and for the passage of the spikes C, and seated on the spring *a* in the block A, substantially as and for the purposes described.

OLIVER GUINAND.
